UNITED STATES PATENT OFFICE.

WILLIAM E. FISCHER, OF BOSTON, MASSACHUSETTS.

CHANNEL-FLAP TURNER.

SPECIFICATION forming part of Letters Patent No. 588,970, dated August 31, 1897.

Application filed October 9, 1896. Serial No. 608,410. (No model.)

To all whom it may concern:

Be it known that I, WILLIAM E. FISCHER, of Boston, county of Suffolk, State of Massachusetts, have invented an Improvement in

5 Channel-Flap Turners, of which the following description, in connection with the accompanying drawings, is a specification, like letters on the drawings representing like parts.

This invention has for its object the production of a novel machine for turning over the flaps of channels cut in leather soles, my present improvements adding greatly to the efficiency of the machine.

I have devised a novel feeding mechanism, 15 the same presenting two wheels working side by side, the shaft carrying and actuating said wheels being so supported that the center of rotation of one of said wheels may be readily varied with relation to the center of rotation 20 of the other of said wheels, such change of center enabling one of said wheels to engage the inner face of the sole near its edge to feed the sole, while the other of said wheels supporting the sole near its median line may yield 25 somewhat as the wiper to be described acts on and lays the channel-flap over, such yielding of the said wheel obviating putting so much strain on the flap as to tear the same. These 30 wheels may be adjusted vertically as to their position, and their relative levels may also be varied by adjusting devices.

In this my improved machine the shaft carrying the wiper revolves in a yoke adapted to turn about a vertical pivot erected on a horizontally-sliding frame, such construction enabling the said wiper to be adjusted toward and from the feed-wheels to accommodate the machine to the particular diameter of the wiper used or to enable the said wiper to 40 be adjusted so as to occupy a position entirely beyond the feed-wheels, so that the operator, holding a lasted shoe in his hand, it having laid on it a channeled outer sole, may have the flap of the said channel turned or 45 laid back while the outer sole is in position on, but firmly fixed to, the inner sole.

By moving the yoke having the bearings for the wiper-shaft aside about the vertical pivot the wiper may be readily changed and 50 one of the desired diameter or thickness put in place, and then the said yoke may be moved back again into the desired position over the

foot or presser, which bears on the sole in opposition to the feed-wheels, the free end of said foot also entering the channel and serving as a guide. 55

I have made the flap-holder adjustable to adapt it to the diameter of the wiper used, and I have also made provision for adjusting the normal position of the wiper according 60 to its diameter. The foot or presser referred to has also been made adjustable to adapt it to the diameter of the wiper. I have also mounted the idlers on a movable yoke, so that they may be readily adjusted to enable the actuating-belt to be driven from a pulley below the bench on which the machine sits or from shafting above the bench. 65

The shafts carrying the feed-wheels are located one inside the other and are supported 70 in a pivoted frame.

The yoke carrying the bearings for the wiper-shaft is made vertically adjustable with relation to the foot or presser.

Figure 1, in front elevation, represents a 75 channel-flap-turning machine embodying my present improvements; Fig. 2, a right-hand side elevation thereof, partially broken out, the parts being in position to wipe back a flap of a channel made in a sole which will 80 rest on the feeding-wheels. Fig. 3 is an enlarged section on the line x, Fig. 2. Fig. 4 is a detail showing the manner of connecting the two shafts carrying the feed-wheels. Fig. 5 is a detail showing the manner of adjusting 85 the position of the yoke carrying the wiper-shaft. Fig. 6 shows the hub b' detached. Fig. 7 is a section of one of the parts of the feed-wheel b'; Fig. 8, a top view of the wiper and part of the spindle to which it 90 is attached. Fig. 9 shows the flap-presser in plan view with its shank in section. Fig. 10 is a sectional detail to be referred to, and Fig. 11 a rear view of the yoke C'.

The base or frame A, of suitable shape to 95 support the working parts, has a projection a, which enters a groove a' in an upper frame A', a screw a² entering a screw-threaded opening in the rib a³ of the base A and extending through a slot a⁴ in the bottom of the upper frame, permitting the upper frame to be adjusted longitudinally upon the lower frame and to take with it the parts carried thereby to be described. 100

The base has a suitable stud upon which is mounted the driving-wheel B, the hub of which is provided with a pinion B', said pinion engaging a toothed wheel B², fixed upon the right-hand end of a hollow shaft B³, having its bearings in a frame B⁴, pivoted at B⁵, the center of said pivot being coincident with the pitch-line of the gears B' and B², so that said frame may rise and fall at its outer or left-hand end.

The shaft B³ is a hollow shaft, and it has attached to its outer end by a suitable set-screw, as b, (see Fig. 2,) a hub b', (shown detached in Fig. 6,) said hub having a projecting flange b³ and being provided with a series of adjusting and holding screws b². The feed-wheel next to this hub and held by the set-screw is made in sections, as best shown in Fig. 3, where the said sections are designated by the letters b⁵, the inner side of said feed-wheels next to said hub having grooves b⁶, in which enter the points of the screws b², the said grooves and the points of the screws being so shaped that when the parts of said wheels are put into position to be confined in the machine said screws are turned in to confine the sections of the wheel in place, act against one wall of said groove to force the said wheel-section against the flange b³ of the hub, and at the same time they move the sections of the wheel toward each other in order that they may be locked firmly against the outside of the neck b⁷ of the hub.

Fig. 7 shows a section of one of the parts of the wheel b⁵ and with the point of a set-screw entering the groove b⁶.

The feed-wheel c has its hub attached by a suitable set-screw c' to a shaft c², threaded at its outer end, as represented in Fig. 10, the end of the shaft being mounted in a bearing c⁸, made as a square block sustained in a slotted link c⁴ by a spring c⁵, said spring being adjustable by a nut c⁶ on a rod c⁷, also sustained in the slot of said link, the lower end of the link being pin-jointed at c⁸ to a lever c⁹, pivoted at c¹⁰ on the vibrating frame B⁴, the said lever c⁹ having attached to it a rod c¹², which in practice will be connected with a suitable treadle at the floor, so that by pressure upon the said treadle the lever may be turned to raise the outer end of the shaft c², and consequently the wheel c, and place its periphery above the periphery of the wheel b⁵, and in this position of the parts the wheel c alone becomes the feeding-wheel and it alone supports the work.

For turning the flap on Goodyear inner soles I may change the position of the nut c¹³ on the screw c¹⁴, so that said nut will act upon the arm c¹⁵, extending from the lever c⁹ and hold the feed-wheel c elevated above the feed-wheel b⁵, and then I adjust the frame A' to the left to put the foot e⁴ in position to hold the work on the feed-wheel. The nut c¹⁶ limits the movement of the lever c⁹ when actuated by the foot of the operator. The spring c⁵ holds the feed-wheel c up with a yielding

pressure, so that it may move vertically to a limited extent with relation to and across the face of the feed-wheel b⁵. The frame B⁴ is free to yield up or down as it rests upon the spring d, made adjustable in usual manner, the said spring keeping the frame and the two feed-wheels in their operative positions. The shaft c² is extended through the hollow shaft B³ and rotates coincidently with it; but in order to enable the wheel c to move vertically with relation to the wheel b⁵ the connection between the two shafts may be a sort of universal connection. I have shown this universal connection in this instance of my invention as a tri-armed spring d', attached by screws d² to the gear B², the said shaft being extended through a hole in the center of the said spring and having applied to it suitable adjusting-nuts d³ and d⁴. (See Fig. 4.) Instead of this three-armed spring I might readily use any usual form of gimbal-joint.

I have added to the base A a wedge-block e, (shown in Fig. 2 partially by dotted lines,) and have made the same adjustable by or through a suitable screw e', the adjustment of said wedge limiting the upward position of the frame or lever B⁴ and the plane in which the feed-wheel may normally stand, and to lock the feed-wheel and frame down in inoperative position I may depress the inner end of the frame and insert in a hole e² a suitable pin, it crossing the bearing in which the shaft B³ rotates, this being done when the upper frame a' is pushed far enough to the left to place the wiper to be described entirely beyond the feed-wheels, so that the operator can hold the outer sole applied to a lasted shoe up against the under side of the foot e⁴, said foot being also in the channel.

The upper frame has a standard C, to which is attached a yoke C' by a suitable screw C^X, (shown in Fig. 11,) said yoke having at its ends diagonally-placed studs C², upon each of which is hung an arm C³, having a suitable stud C⁴, upon which is mounted one of the idler-wheels C⁵.

The upper frame A' has erected upon it a vertical pivot or stud D, upon which is fitted to turn the hub of a yoke D', having suitable bearings for the wiper-shaft D², provided with a wiper f, having suitable lips f' and shown in plan view in Fig. 8, the said wiper being threaded at its center to be screwed onto a thread at the lower end of said shaft.

The shaft has attached to it by suitable screws f² a sleeve-whirl, the large part of the sleeve-whirl D² having a belt-receiving groove f³, it surrounding but not touching the upper bearing f⁴ for sustaining the said shaft, and consequently the upper bearing is not at all strained by the belt-pull.

In Fig. 2 the belt or band f⁵ is supposed to be driven from a pulley below the bench on which the machine sets, but should it be desirable to drive the said spindle from a pulley above the bench in such case the screw C^X will be withdrawn and the yoke C' will be

turned over one-half way, leaving the arms C^3 standing above their pivots C^2 , such reversal of the yoke maintaining the proper pivotal relation of the arms C^3 , so that the strain of the belt on the pulleys will be in line with the pivots C^2 , the acting face of the elevated idle-pulley c^5 coming in line with the center of the grooved pulley f^3 of the whirl.

The hub of the yoke D' rests on a spring D^6 , and the upper end of the stud D receives a screw D^7 , the inward turning of the screw depressing the yoke against the spring and the outward turning of the screw permitting the spring to raise the yoke, and when the yoke is in its proper position vertically it will be locked in said position by a set-screw D^8 , acting against the stud D . The upper end of this stud (see Fig. 5) is slabbed off for part of its diameter, as at g , and a screw g' in the hub of the yoke may be turned in the said yoke more or less in order to coöperate with the said slabbed part and limit the axial motion of the hub of the yoke D' on the stud when the yoke is turned to put the wiper-shaft in operative position, this position being changed to accommodate the diameter of the wiper to be used.

The wipers are changed from time to time, according to the particular shape or size of the channel in the sole and thickness of flap, and to effect this change readily the set-screw D^8 may be loosened and the yoke D' may be turned about the vertical stud D , after which the wiper may be readily turned off and one of the proper size or diameter and thickness applied.

The wiper acts substantially as the wiper described in my Patent No. 128,610, dated July 2, 1872, and coöperating with said wiper is a flap-holder h , (shown separately in Fig. 9,) its under side being shaped to act upon and hold in its turned-over position the flap as the latter is opened over to uncover the channel. This flap-holder is adjustably attached by a screw h' to a horizontally-adjustable block h^2 , in turn attached to the yoke by an adjusting-screw h^3 , so that the said flap-holder may be adjusted horizontally, as well as vertically, to adapt it to coöperate with a wiper of any desired diameter and also to adapt it to the varying thicknesses of the wiper.

The foot e^4 is made adjustable on the upper frame A' horizontally, as shown by a suitable set-screw h^4 .

In applying the feed-wheel c to its shaft its hub is acted upon by the inner end of the bearing c^3 , a washer m placed against the outer side of said bearing and acted upon by a nut m' , forcing the bearing against the hub of the feed-wheel and forcing the face of the feed-wheel substantially against a small collar m^2 , (see Fig. 11,) and thereafter the set-screw c' is screwed in to fasten the wheel upon the shaft.

The feed-wheels herein shown and described

may be used in connection with machines for channeling.

Making the inner feed-wheel b^5 in section enables it to be readily removed from the driving-shaft after the teeth may have become dull by wear, and another wheel-section, preferably made of steel, may be inserted instead of it, thus obviating sharpening the teeth, as heretofore done.

When wiping the flap back about the toe of the sole, the operator will by his foot lift temporarily the feed-wheel c , thus lessening the pressure of the sole on the feed-wheel b^5 , which has the longer teeth, so that the sole may be turned in a small curve and the teeth of the wheel b^5 will not injuriously mar its surface.

The screw C^X , forming the pivot for the yoke C' , occupies a position in the horizontal plane with the straight horizontal run of the belt f^5 .

Viewing Fig. 3, it will be seen that the shaft c^2 is located at one side of the center of the surrounding shaft B^3 , this being effected by locating the bearing c^3 for the outer end of the shaft c^2 at one side of the center of rotation of the shaft B^3 , such location of said shaft c^2 resulting in placing the centers of the two feed-wheels at a distance from each other, which puts the acting peripheries of said wheels normally in such position with relation each to the other as to constantly present a layer surface to support the sole.

I have shown pointed set-screws as a means for attaching the feed-wheel sections to said hub, but the invention is not limited to just the means shown for attaching the feed-wheel sections in position, and I believe that I am the first to use a feed-wheel in section and hold it in place by independent devices.

Having described my invention, what I claim as new, and desire to secure by Letters Patent, is—

1. In a channel-flap-turning machine, two rotatable feed-wheels located side by side, means to enable the said feed-wheels to be moved the face of one substantially parallel to the face of the other to adapt said wheels to the work to be done, and a foot to hold the work on said wheels, combined with a wiper-shaft, an attached wiper, a flap-holder and means to rotate said wiper-shaft and cause said wiper to act on and turn over the flap of a sole supported by said wheels, substantially as described.

2. In a machine of the class described, a feed-wheel, a foot to bear on the sole, a rotatable wiper-shaft having a wiper, and a yoke having bearings for said shaft, combined with a vertically-placed stud located at one side of and parallel to said shaft, and means to effect the rotation of the said yoke about said stud when it is desired to remove or replace a wiper, substantially as described.

3. The yoke, the hollow shaft having bearings therein, the shaft c^2 carrying the feed-

- wheel *c* fixed thereon at a short distance from its outer end to thus leave the outer end of said shaft exposed, an outer bearing to receive the end of said shaft, a link to contain and 5 guide said bearing, and a spring coöperating with said link to keep said bearing pressed upwardly with a yielding pressure, combined with an independent lever to raise and lower said link, substantially as described.
- 10 4. In a machine of the class described, the wiper-shaft, its attached wiper, the yoke having bearings for the said shaft, and a slabbed stud serving as a pivot for said yoke, combined with an adjustable stop carried by said yoke and coöperating with the slabbed part 15 of the said stud to position the said yoke and wiper, substantially as described.
5. In a machine of the class described, the wiper-shaft, its attached wiper, the yoke having 20 bearings for said shaft, and a vertical stud serving as a pivot for said yoke, combined with devices to adjust said yoke vertically on said stud, and means to restrain the rotation of said yoke on said stud during the operation 25 of the same, substantially as described.
6. In a machine of the class described, a wiper-shaft, its attached wiper, and bearings for said shaft, combined with an adjustable foot interposed between said wiper and the 30 bottom of the channel having the flap to be overturned by the said wiper, substantially as described.
7. The feed-wheel *b*⁵, the hollow shaft carrying it, the feed-wheel *c* and its shaft, and 35 bearing for its outer end, combined with a link carrying said bearing, and means to move said link to change the position of the acting periphery of the wheel *c* with relation to the acting periphery of the wheel *b*⁵, substantially as described.
- 40 8. The feed-wheel *b*⁵, the hollow shaft carrying it, the feed-wheel *c* and its shaft, and bearing for its outer end, combined with a link carrying said bearing, a spring carried 45 by said link and acting on said bearing, and means to move said link to put the acting periphery of the wheel *c* above the acting periphery of the wheel *b*⁵, substantially as described.
- 50 9. The shaft *c*² having the feed-wheel *c* fixed thereon near its end but so as to leave the end of said shaft exposed beyond said feed-wheel, an outer bearing in which the outer end of said shaft is placed, a link in which said bearing is free to slide and a spring acting on said bearing, combined with a lever to act on and lift said link, substantially as described.
- 55 10. In a machine of the class described, a shaft and an attached feed-wheel, combined 60 with a second shaft and a feed-wheel composed of a plurality of segmental pieces which may be moved laterally, substantially as described, with relation to said shaft, when applying a wheel to or removing a wheel from said shaft, substantially as described.
- 65 11. In a machine of the class described, two feed-wheels located side by side, means to ro-

tate said feed-wheels in substantially parallel planes, and means to change the position of the periphery of one of said wheels with 70 relation to the periphery of the other of said wheels, substantially as described.

12. In a machine of the class described, two feed-wheels applied side by side, means to rotate said feed-wheels, and independent yielding supports to enable said feed-wheels to yield independently one of the other, substantially as described.

13. In a machine of the class described, two feed-wheels applied side by side, and means 80 to rotate said feed-wheels, combined with means to elevate one of said feed-wheels so that its periphery will sustain and feed the work and release the other of said feed-wheels from the duty of supporting and feeding the 85 work, substantially as described.

14. In a machine of the class described, two feed-wheels located side by side, means to rotate said feed-wheels, and means to elevate a 90 part of the periphery of one of said feed-wheels with relation to the periphery of the other of said feed-wheels, combined with a foot located above the axis of both of said feed-wheels to act on the work resting on said feed-wheels, and means to adjust said foot toward 95 and from said feed-wheels in a horizontal direction and at right angles to the plane of rotation of said feed-wheels, substantially as described.

15. In a machine of the class described, two 100 shafts, one located within the other, two feed-wheels, one attached to the end of one and the other to the end of the other of said shafts, a pivoted frame constituting a bearing for the outer one of said two shafts, and means to 105 hold the bearing for the inner shaft to one side of the center of rotation of the outer shaft, substantially as described.

16. In a machine of the class described, a hollow shaft provided with a feed-wheel and 110 having an attached gear, a pivoted frame in which said hollow shaft has its bearings, said frame having its pivotal point in the pitch-line of said gear and pinion, combined with a shaft extended through said hollow shaft 115 and provided with a second feed-wheel, substantially as described.

17. The hollow shaft, its attached feed-wheel and gear, and a shaft extended through said hollow shaft and provided with a second feed-wheel, combined with a universal connection 120 between said two shafts whereby the inner shaft may vibrate in the hollow shaft during their rotation, substantially as described.

18. The hollow shaft, its attached gear, and 125 feed-wheel, and the feed-wheel *c* and its shaft *c*² extended through said hollow shaft, said feed-wheels lying side by side, and an annular spring-support for one end of said shaft *c*², said spring-support being connected to 130 said gear, said shaft and feed-wheels rotating coincidently, yet being free to change relatively their vertical positions, substantially as described.

19. The feed-wheel c , its shaft, its outer bearing, a link containing said bearing, and a spring acting on said bearing, combined with a lever to act on and lift said link, and means to control and stop the uppermost position of said lever, substantially as described.

20. The shaft, its attached hub having a flange, and the segmental toothed plates constituting a sectional feed-wheel, combined with pointed set-screws carried by said hub and coöperating with beveled portions of said wheel-sections to engage and hold the same firmly in place, substantially as described.

21. The shaft c^2 , its collar, the feed-wheel mounted on said shaft and resting against said collar, combined with the shaft-bearing acting against the hub of said feed-wheel, means to support and guide said bearing, and a nut and washer acting on one end of said bearing to keep the said feed-wheel against said collar, substantially as described.

22. The wiper-shaft, its attached wiper, a yoke having bearings for said shaft, a whirl on said shaft having a groove for a belt, combined with idle-pulleys, arms having studs on which said pulleys rotate, and a reversible yoke having diagonally-placed studs on which said arms turn, whereby said arms may either

depend from or stand above their pivotal points on said yoke, and yet present the belt-sustaining portion of the pulleys in line with the bottom of the belt-groove of the said wiper-shaft, substantially as described.

23. In a channel-flap-turning machine, two rotatable feed-wheels located side by side, means to enable the said feed-wheels to be moved, the side of one substantially parallel to the side of the other to adapt said feed-wheels to the work to be done, and a foot to hold the work on said wheels, combined with a wiper-shaft, an attached wiper, a flap-holder, and means to rotate said wiper-shaft and cause said wiper to act on and turn over the flap of a sole supported by said wheels, and means to adjust said wiper-shaft and foot toward and from the said wheels substantially at right angles to the plane in which they rotate, substantially as described.

In testimony whereof I have signed my name to this specification in the presence of two subscribing witnesses.

WILLIAM E. FISCHER.
